UNITED STATES PATENT OFFICE.

JOSEPH BOUTEILLE, OF PARIS, FRANCE.

INTERNAL-COMBUSTION ENGINE.

1,301,807.

Specification of Letters Patent. Patented Apr. 29, 1919.

Application filed July 29, 1918. Serial No. 247,248.

To all whom it may concern:

Be it known that I, JOSEPH BOUTEILLE, a citizen of the Republic of France, residing at 40 Rue Poussin, Paris, in the Republic of France, have invented certain new and useful Improvements in Internal-Combustion Engines, of which the following is a specification.

The object of the present invention, which relates to explosion motors, and more particularly to those that are intended to work under atmospheric pressures that vary incessantly and considerably, as is the case with motors on aircraft, is to procure for them a power sufficiently independent of the variations in the pressure of the surrounding air, and this within the desired limits, at the same time procuring for them a higher thermal efficiency and obviating the numerous dangers and accidents due to excessive compressions and stresses when the atmospheric pressure is high.

The invention therefore consists in limiting the final compression to a predetermined value that has to remain practically constant notwithstanding the variations in the density and pressure of the surrounding air, eliminating during a portion of the compression period the excess gas drawn in, by connecting the chamber of the motor to a pressure-relieving collector through the medium of a fluid-tight controlled device, such as a valve, and in maintaining in the pressure-relieving collector a maximum pressure regulated by an equally suitable device. The gases flowing back from the pressure-relieving collector may be led back into the main suction pipe either behind or in front of the gas inlet that serves to regulate the power to be obtained from the motor.

The accompanying drawing shows an axial section of a cylinder and shows diagrammatically how the invention may be put into practice.

Let a motor consist of one or more cylinders 1, cooled in any manner, in which there move pistons 2, actuating by means of connecting rods 3, the crank 4. The motor may work on the two stroke or the four-stroke cycle, and in the latter case, as illustrated, let 5 be the exhaust valve and 6 the inlet valve of a normal known method of working. These valves may of course be situated in the various customary positions, or re-

placed by what are called "valveless" arrangements; and let 7 be the chamber called the compression chamber.

The improvement in the motor forming the subject-matter of the invention is to eliminate the excess gas drawn in, which might bring about an excessive compression, by opening a fluidtight device of suitable dimensions controlled by the cam shaft itself, such as the valve 8 during part of the compression stroke, such elimination being effected into a collector 9, in which the pressure of the gases admitted thereto cannot exceed a value regulated by a device such as a delivery valve 10, retained by a regulating spring 11. In the case of multi-cylinder motors a single delivery valve 10 would suffice to regulate the maximum pressure of the gases contained in the pressure-relieving collector 9. The delivery gases will be discharged into the suction pipe 12 for the purpose of being re-used.

The method of working of such an arrangement will be understood in the following manner:—The crank 4 is assumed to be revolving in the direction of the arrow 13, the suction stroke commencing when the end of the connecting rod is in the neighborhood of the position *a* and finishing at *b*, from which point the compression stroke will commence. If at *c* the relief valve 8, which may be of comparatively small dimensions, is open, the gases will also come and fill up the passage 9, and if at *d* the same valve 8 is closed there will exist at that moment in the compression chamber 7, the portion of the cylinder not yet swept by the piston, and the pressure-relieving chamber 9, a pressure regulated by the delivery valve 10. If therefore at one and the same point *d* the compression bears a constant relation, invariably or almost invariably, to the quantity of gas admitted, from *a* to *b*, the final compression at *e* will also be constant, and will not in any case, if the adjustments are properly effected, be able to exceed the value that would bring about an explosion that the parts of the motor would not be able to stand.

An aircraft motor provided with such an arrangement, designed and adjusted for normal working and compression at high altitudes, will have its power but little augmented when on the ground, and its light parts will not be subjected to any excess load.

capable of impairing them. Of course the diagrammatic drawing is only given here by way of example, and does not limit the scope of the present invention at all, and all 5 motors comprising the new arrangements thus described, and summarized hereunder, pertain thereto.

What I claim and desire to secure by Letters Patent of the United States is:—

10. 1. An internal combustion engine comprising means for producing a substantially uniform compression in the explosion chamber, said means including means for allowing the explosive mixture to escape 15 from the said chamber at a predetermined position of the piston in the compression stroke.
20. 2. An internal combustion engine comprising means for producing a substantially uniform compression in the explosion chamber, said means including means for allowing the explosive mixture to escape from said chamber at a predetermined position of the piston in the compression 25 stroke and means for returning the escaping mixture to the suction pipe of the engine.
30. 3. An internal combustion engine comprising means for producing a substantially uniform compression in the explosion chamber, said means including a collecting chamber having a connection to the explosion chamber and a positively controlled valve adapted to be opened during the compression stroke and closed at a predetermined 35 position of the piston.
40. 4. An internal combustion engine comprising means for supplying explosive mixture to the explosion chamber, and means independent of said means and operative 45 during the compression period to withdraw

from said chamber the explosive mixture in excess of a predetermined uniform amount.

5. An internal combustion engine comprising a supply pipe for the explosive mixture; a valve controlling the supply of explosive mixture from said pipe to the explosion chamber, and means independent of said valve and operative prior to the ignition of the explosive mixture to return from said chamber to said pipe the explosive mixture in excess of a predetermined uniform amount. 45 50

6. An internal combustion engine comprising means for producing a substantially uniform compression in the explosion chamber, said means including a collecting chamber having a connection to the explosion chamber, a positively controlled valve opening inwardly of said chamber, said valve being adapted to be successively opened and closed at predetermined positions of the piston in the compression stroke, and a relief valve controlling the escape of the explosive mixture from said collecting chamber. 55 60

7. An internal combustion engine comprising a circuit of three valves, one to close the explosion-chamber about when compression begins, the second to allow surplus gases to escape from said chamber as soon as the pressure within it exceeds a predetermined value and the third to prevent this escape at a predetermined position of the piston toward the end of the compression stroke. 65 70

In testimony whereof I affix my signature in presence of two witnesses.

JOSEPH BOUTEILLE.
